UNITED STATES PATENT OFFICE

EDWARD G. YOCHHEIM, OF RITTMAN, OHIO, ASSIGNOR TO THE OHIO BOXBOARD COMPANY, OF RITTMAN, OHIO, A CORPORATION OF OHIO

GRAVE VAULT COVER

Application filed January 6, 1931. Serial No. 506,935.

This invention relates to grave vault covers, that is to say, wrappers or containers in which the grave vaults may be enclosed for protection when shipped.

5 The grave vaults referred to are of the type employed as protective containers for coffins, and replace the ordinary rough wooden box. These grave vaults are customarily made of sheet metal, preferably sheet 10 steel, and have their outer surfaces finished to produce an ornamental, attractive appearance. They may be polished, plated, enamelled, painted, lacquered or otherwise appropriately treated to produce this exterior finish.

In order to protect the finish of these grave vaults when they are shipped, it is the practice of the manufacturers to enclose them in fibreboard containers or covers which ordinarily 20 comprise a longitudinal wrapper member passed around the whole length of the vault and wired in place thereon, and end pieces having tuck-in flaps which latter are inserted between the wrapper and the 25 sides of the vault to hold the end pieces in place, the meeting edges of the ends of the wrapper and of the end pieces being externally 30 taped to exclude foreign matter.

It has been found that grave vault covers thus constructed and applied are not entirely satisfactory, due to the fact that, because of play between the wrapper members and end pieces, or from other causes, the ends of the grave vaults become chafed and their finish 35 thus marred.

It is the object of the present invention to so construct and apply grave vault covers that this chafing and marring will be done away with.

40 To this end the invention consists in a grave vault cover comprising a wrapper member arranged longitudinally of the grave vault and held in place thereon by bands of wire or other suitable material, this wrapper member extending to the ends of the grave vault and terminating adjacent thereto, the ends of the wrapper member being provided with flaps or extensions adapted to be folded 45 in against the ends of the grave vault; and end pieces applied against these flaps out of

contact with the ends of the grave vault and secured to the wrapper member, as will be explained more fully hereinafter and finally claimed.

In the accompanying drawing illustrating 55 the invention, in the several figures of which like parts are similarly designated, Figure 1 is a perspective view of a grave vault having the cover of the invention applied thereto, parts being broken away in the interest of 60 clearness. Fig. 2 is a fragmentary perspective view of one end of the wrapper member illustrating the formation of the flaps. Fig. 3 is a view similar to Fig. 2 but showing the flaps folded in. Fig. 4 is a perspective view 65 of one form of end piece. Fig. 5 is a perspective view of a modified form of end piece.

The grave vault 1 shown, is of a conventional type having an arched top 2, and relatively plain vertical sides 3 and ends 4, and the grave vault cover is made of a size to fit the vault with which it is to be used and is so formed that it will substantially conform to the shape of the vault and fit same relatively 75 snugly.

The wrapper member of the cover is preferably made of a single piece of relatively stiff, form-retaining fibreboard suitably scored or creased longitudinally at 5 and 6 so that it may be readily bent to form a top 80 7 and sides 8 and 9 which, when the wrapper member is in proper position upon the vault, will properly embrace the top 2 and sides 3 thereof and extend the full length of such top and sides. No covering is provided for 85 the bottom of the vault, and none need be, because the bottom is not finished and need not be protected.

Both ends of the wrapper member are 90 provided with tabs or flaps 10, 11 and 12 forming parts of the top 7 and sides 8 and 9 respectively, and these flaps are adapted to be folded in substantially flat against the ends of the vault, as indicated in Figs. 1 and 95 3. In order that the flaps 10 of the top 7 may not overlap or bunch when folded upon the curve of the arch of the vault, they are separated by notches or wide slits 13. The extent of the flaps 10, 11 and 12 is defined by 100

scores or creases 14, 15 and 16 which facilitate their proper folding.

5 Bands or straps 17 of wire or other suitable material are passed around the vault and wrapper member and appropriately secured to hold the wrapper member in adjusted position.

10 After the wrapper member is thus applied, with the end flaps folded in against the ends of the vault, the end pieces, either of the form shown in Fig. 4 or in Fig. 5, are applied, and all edges taped, as indicated at 18, Fig. 1, with suitable gummed tape to exclude dust, grit and other foreign matter.

15 The end pieces of the form shown in Fig. 4 have a body portion 19 and side flaps 20 and 21 foldable upon creases or scores 22 and 23, whereas those of the form shown in Fig. 5 comprise merely a flat piece 24. Both forms 20 are shaped to conform substantially to the shape of the ends of the vault, and they are made, preferably, of fibreboard like the wrapper member.

25 When the form of end piece shown in Fig. 4 is used, it is applied with its body portion 19 flat against the flaps 10, 11 and 12 and affixed thereto by means of a suitable adhesive, and its side flaps are applied to the outside of the sides 8 and 9 of the wrapper member and 30 similarly affixed thereto, and all the edges are taped, all as illustrated in Fig. 1.

35 When the form of end piece shown in Fig. 5 is used, it is applied and affixed to the flaps 10, 11 and 12 by adhesive and all edges are taped.

40 It will be apparent that if the flaps 10, 11 and 12 are omitted, as is the case with covers of known types hereinbefore referred to, the end pieces when applied will contact directly with the ends of the vault and any movement between them and the wrapper member, and hence between them and the ends of the vault to which the wrapper is relatively fixedly applied, will result in chafing and marring of the ends of the vault. This is particularly true in case foreign substances have intruded.

45 It is to be noted, however, that in the cover of this invention the flaps 10, 11 and 12, which 50 are preferably integral with the wrapper member, carry the end pieces and support them out of contact with the ends of the vault. Thus, inasmuch as the wrapper member and its flaps 10, 11 and 12 are substantially fixed relatively to the vault, there can be no chafing of the vault and it will not be marred or defaced.

55 Various changes and modifications are considered to be within the spirit of the invention 60 and the scope of the following claim.

What I claim is:

65 A grave vault cover, including a wrapper member of such form as to extend longitudinally of the vault from end to end thereof and having portions to cover the top and

70 sides of the vault, said wrapper provided at its ends with flaps extending from said top and side covering portions and adapted to be folded inwardly into contact with the ends of the vault, and end pieces applied to said flaps and supported thereby out of contact with the ends of the vault.

75 In testimony whereof I have hereunto set my hand this third day of January A. D. 1931.

EDWARD G. YOCHHEIM.
